UNITED STATES PATENT OFFICE.

OTIS A. MYGATT, OF NEW YORK, N. Y.

DESIGN FOR A REFLECTOR FOR ARTIFICIAL LIGHTS.

No. 37,808.

Specification for Design.

Patented Feb. 6, 1906.

Application filed December 5, 1903. Serial No. 183,978. Term of patent 14 years.

To all whom it may concern:

Be it known that I, OTIS A. MYGATT, a citizen of the United States, residing at New York, in the county of New York and State of New York, have invented a certain new, original, and ornamental Design for a Reflector for Artificial Lights, of which the following is a specification, reference being had to the drawings, forming part thereof.

Figure 1 is a side elevation, and Fig. 2 a bottom or interior plan, of a reflector embodying my design.

The reflector is composed of glass. The

outer surface of the reflector proper is covered with radial reflecting-prisms, terminating in beads at the edge of the reflector. The inner surface is smooth. The lower edge is crimped in accentuated scallops.

What I claim is—

The ornamental design for a reflector, as shown and described.

OTIS A. MYGATT.
